ELECTRICAL CONNECTOR

Charles N. Metcalf, Port Chester, N. Y., assignor to
 Consolidated Edison Company of New York,
 Inc., New York, N. Y., a corporation of New
 York

Application March 21, 1940, Serial No. 325,101

5 Claims. (Cl. 287—78)

This invention relates to connectors for electrical cables or other conductors.

According to the invention, connectors may be provided of a form particularly adaptable for connecting tap-off wires or cables to a main cable without severing the main cable, although certain features of the invention are also adaptable to various other applications. The invention provides an improved connector of the so-called compression type, that is, of a type which may be applied to the conductors and then subjected to pressure for permanently deforming the parts, to provide fixed engagement with the conductors or to tighten the embrace of the device upon the cables or wires, without bolts and screws or the like.

Heretofore cable tap-off connectors have been available in various forms including devices adapted to be clamped to the cables by the use of screws, and any other forms ordinarily quite bulky and expensive, and requiring considerable time and labor for their application and subsequent proper insulation. Types which have bolts and screws or the like are liable to become loosened upon heating and cooling of the cables, thus impairing the electrical conductivity of the joint. Also such types, particularly if they have protruding parts, are very difficult to properly insulate without forming a bulky and unsightly joint. That is, the protruding parts not only obstruct the winding of the joint with insulated tape, but tend to injure the insulation, and require that numerous layers be applied to safely cover the protruding parts. Also with a recently developed procedure for insulating cable joints, pads or masses of soft rubber composition, unvulcanized or partially vulcanized are first applied to the joint and subsequently covered by tape. With such compositions it is of importance that the connector be free of parts such as bolts and nuts which will tend to protrude through the inner soft insulating material.

In other cases, in efforts to avoid the time and skilled work required to properly insulate cable tap-off joints, resort has been had to relatively bulky connecting members previously insulated in the factory and into which the cable ends may be secured as by sweating with solder. But aside from the expense and awkward size of such devices, it is necessary to cut the main cable and thus interrupt the power service in order to apply the device.

The present invention in its preferred forms obviates the above difficulties and also provides a very compact, inexpensive connector which may

be cheaply and quickly applied and safely insulated without severing the main cable or interrupting the power service, and with which the cross sections of the resulting joint, if insulated, need not very substantially exceed in size the cross sections of the insulated cables connected. The invention also provides a connector of exceptional mechanical strength which will remain fixed firmly to both the cable and the tap-off conductor, and permanently maintain an electrical connection of high conductivity between the two, even under severe operating conditions, and without the necessity, troubles and uncertainties of using solder on the job.

In the drawing,

Fig. 1 is a perspective view showing the parts of a preferred form of connector embodying the invention;

Fig. 2 is an end view of the same parts as applied to a main cable and a tap-off cable, but showing the parts prior to application of compressive force thereto for fixing the same in position;

Fig. 3 is a view of the device, somewhat similar to Fig. 2 but showing the cross-sectional shape of the parts and of the cables after the assembly has been compressed and fixed in position, and also showing portions of the apparatus for compressing the connector;

Fig. 4 is a side view of a completed joint using a connector according to the invention, the parts being shown prior to application of insulation thereto;

Fig. 5 is a top view of the assembly shown in Fig. 4, and

Fig. 6 is a perspective view of portions of an alternative embodiment of the invention.

As shown in Fig. 1, the preferred form of the connector may comprise a pair of generally cylindrical portions as at 10 and 11 secured together in side-by-side relationship and each adapted respectively to separately receive and embrace a cable or tap-off conductor. The portions 10 and 11 may be formed of sheet metal or metal of a sheet-like character preferably of medium hard drawn copper or other metal of high electrical conductivity, and having considerable firmness and rigidity while being adapted to be permanently deformed in a manner hereinafter described. The members 10 and 11 may if desired be made separately of sheet metal and then bent into the forms shown and secured together as by silver solder at 12. Or if the connectors are to be made in large quantities, it may be found desirable to integrally form the portions 10 and 11

by extruding a continuous piece of metal of this shape, which may be cut into sections to form connector units as of Fig. 1.

It will be observed that the portion 10 at the 5 side opposite from the portion 11 is formed with a gap or opening as at 13 whereby the portion 10 may be applied to a cable without severing the cable. In the preferred form shown, the opposite edges extending along the gap or opening 13 may 10 be bent downwardly, outwardly and then slightly upwardly as shown, to form oppositely directed channels as at 14 and 15 extending lengthwise of the main cable. The area of the gap or opening 13 is adapted to be covered by a slidably applied 15 cable member 16 formed on its upper surface with inwardly directed channels as at 17 and 18. That is, the channel portions 17 and 18 are adapted to slidably engage and interconnect the channel portions 14 and 15 in a manner apparent at the 20 bottom of Fig. 2.

To apply the member 16 as shown in Fig. 2, the portion 10 is first placed around a portion of a main cable as at 19 at an area where the insulation has been removed. Thereupon the channel portions 14 and 15 may be forced more closely together as by the use of pliers or other instrument with suitably shaped jaws, to engage the channel portions 14 and 15 without injury. Then while the portions 14 and 15 are being held nearly together, the member 16 may be slid on endwise, or forced on by endwise tapping to the position shown in Figs. 2 and 4. At this time while the portion 10 may more or less firmly embrace the cable 19, it is not intended that the connector will as yet be necessarily fixed in position with sufficient firmness to permanently insure the parts against displacement, or to insure a permanent satisfactory electrical contact with the cable. As will be noted in Fig. 2, there is still preferably a small gap 20 between the channel portions 14 and 15. Thus there is room for these portions to be brought closer together for tightening the band portion 10 with the cable 19 under high compression therein. The manner in which this may be accomplished will be explained below in connection with Fig. 3.

The member 16 may preferably be formed of metal somewhat more rigid than the portions 10 and 11, although it need not be a metal of high 50 electrical conductivity since it is not interposed electrically between the cables. It has been found that the member 16 may be satisfactorily made of relatively hard phosphor bronze and with the proportions and shape as shown, it will be capable 55 upon slight deformation as hereinafter described, of permanently interconnecting the channel portions 14 and 15 while the cable is very tightly embraced.

After the portions 10 and 16 have been assembled in respect to a main cable as shown in Fig. 2, the end of a tap-off cable or other conductor as at 21 may be introduced into the portion 11 as shown. The portion 11 may be of such dimensions as to rather closely fit the end of the tap-off 65 conductor or may if desired be more closely fitted as by the use of a simple cylindrical adaptor.

The assembly is now ready to be subjected to compression for permanently fixing the parts in place with the cables therein. For this purpose suitable connector presses of types heretofore 70 known may be used. Such presses may be operated hydraulically, mechanically, or by an explosive discharge. One example of such a press is described and illustrated in an article of which 75 the applicant is a joint author, published in the

"Electrical World" for January 15, 1938, page 128 (258). The portions of such a press which come into immediate contact with the connectors of this invention are shown in Fig. 3 as comprising a lower jaw member 22 for engaging the connector portion 16, and a depressible plunger 23 having a protuberance as at 24 for engaging the upper surface of the connector portion 11. 5

It will be noted that the lower jaw 22 is so shaped that when pressure is applied, the side 10 edges of the member 16 will be tilted upwardly slightly or in other words, the portion 16 will be given a curvature tending to conform somewhat with the curvature of the band portion 10 and of the cable therein. In this way the channel 15 portions 17 and 18 on member 16 will be brought more closely together, thus forcing the channel portions 14 and 15 more closely together or into contact, whereby the cable 19 is gripped in a powerful embrace by the band 10. Meanwhile 20 the protuberance 24 on the depressible plunger will permanently deform the connector portion 11 at its middle section, into the shape shown in Fig. 3, at the same time deforming the shape of the tap-off cable 21 therein in such a way as to 25 interlock the connector portion 11 with the tap-off cable and to also hold the latter in a powerful embrace, insuring permanent good contact. The downward pressure may also deform the main cable 19 into a somewhat elliptical shape 30 as shown, which will better insure good and firm contact, but without danger of injuring the cable.

The upper surface of the connector portion 11 may be initially formed with a slight depression as at 25 if desired for receiving and properly 35 centering the protuberance 24 of the press plunger. After the pressure is applied, the upper surface of connector portion 11 will have a deep central depression, for example, such as at 26 (Figs. 4 and 5), penetrating into the tap-off cable 40 sufficiently to amply secure the tap-off against ever being pulled out of the connector.

The alternative embodiment of the invention shown in Fig. 6 may be similar to that above described, except that the upper portion 11', instead 45 of being formed of sheet metal, may comprise a section of tubing or a section of a rod drilled with a central aperture as at 27 for receiving the tap-off conductor. This member 11' may be suitably milled as at 28 to properly fit the member 10' at the area where the two are soldered together. Also the upper surface of the member 11' may be milled or otherwise formed with a groove as at 29 corresponding in function to the groove 25 above described. The construction of 55 Fig. 6 may be found more inexpensive and convenient in cases where it is desired to secure a relatively small tap-off wire to a considerably larger main cable. In respects other than above described, the embodiment of Fig. 6 may be constructed and used in a manner similar to the connector of Fig. 1.

In addition to the advantages of this invention as hereinabove noted, it may be pointed out that the construction being such that the two 65 cables are separately embraced, in the device as finally fixed in position, each cable is wholly encircled by a separate band without any possibility of any appreciable spaces between the bands and the cables which would permit expansion and contraction of the cables and loosening of the bands, and consequent impairment of the conductivity of the connection. Thus the difficulties heretofore encountered in attempting to embrace two cables within a single 70 75

connector band or the like, are avoided. Tests have shown that devices made according to this invention maintain a connection of high electrical conductivity, and do not work loose, even under severe and repeated temperature changes or mechanical strains. It is apparent further that by a single compression operation in a simple type of compressor, the device may be quickly and permanently fixed in position without interrupting the main power supply. That is, the two portions of the device are particularly adapted to be compressed simultaneously by a single operation of the press. The deformation of the parts and of the cables in rubbing contact with each other during the compression, insures satisfactory and permanent electrical conductivity between the two without the use of solder or the like. Hence, the device may be readily installed in places under ground where the use of solder pots and flames are dangerous, inconvenient and troublesome. Also the device when constructed without solder may be used in places where there is danger of the temperature being too high to permit safe use of solder. For outdoor or overhead power line work the invention provides a connector of improved, compact appearance which will withstand any weather conditions without injury.

While the invention has been described in detail with respect to particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A compression type tap-off connector for electrically connecting a main cable without severing same, to a branch wire, comprising a band of sheet-like metal for embracing the main cable, said band initially having an opening on one side to permit its application to the cable, a member adapted to interconnect the edges of the band at said opening after application of the band to the cable, said member being constructed and arranged to then be permanently deformed by compression inwardly of the cable and to thereby tighten the band on the cable, and compressible means fixed on said band at the area opposite from said opening for encircling the branch wire and also so constructed and arranged that said means and said band may be simultaneously fixed to the branch wire and cable respectively by compression inwardly of the assembly.

2. An electric cable tap-off connector applying cable without severing the main cable, comprising a pair of generally cylindrical portions secured together in side-by-side relationship, one of said portions being constructed and arranged for permanent deformation under compression in a direction toward the outer member to embrace and firmly grip the tap-off wire, the other of said portions having a longitudinal opening along its side opposite from said first named

portion to permit application to the main cable, and a slidably applicable member for closing said opening, said member being constructed and arranged for permanent deformation under simultaneous compression in the opposite direction to tighten said other portion on the main cable.

3. In combination with a main cable, means for securing thereto a branch wire or the like, including a band of sheet-like metal embracing the cable, said band being parted along a longitudinally extending line, allowing its application to the cable without cutting the latter, the edges of the band being formed along said line with outwardly and oppositely directed channels, a member covering the parting line and having two opposite edges formed with inwardly directed channels within which said edges of the band are received, said member being permanently deformed under pressure in directions curving same toward conformity with the curvature of the band as embracing the cable, whereby said outwardly directed channels, due to the deforming curvature of said member, are brought sufficiently close together to cause the band to tightly grip the cable, and whereby the channel portions of the band and member are tightly nested together and against the band.

4. In combination with a main cable normally of generally circular cross section, means for securing thereto a branch wire or the like, including a band of sheet-like metal tightly embracing the cable, said band being parted along a longitudinally extending line, allowing its application to the cable without cutting the latter, the edges of the band being formed along said line with outwardly and oppositely directed channels, a member covering the parting line and having two opposite edges formed with inwardly directed channels within which said edges of the band are received, said member being permanently deformed under pressure in directions curving same toward conformity with the curvature of the band as embracing the cable, and the portion of the cable within said band being somewhat deformed to a generally oval cross-section.

5. In combination with a main cable, means for securing thereto a branch wire or the like, including a band of sheet-like metal embracing the cable, said band being parted along a longitudinally extending line, allowing its application to the cable without cutting the latter, the edges of the band being formed along said line with outwardly and oppositely directed channels, a member covering the parting line and having two opposite edges formed with inwardly directed channels within which said edges of the band are received and held sufficiently close together to cause the band to tightly grip the cable, the channel portions of the band and member being tightly nested together and against the band, and another member encircling the branch wire and fixed to said band at a position opposite from said line, the latter member having an area deformed into a correspondingly depressed portion of the branch wire at a position on said latter member opposite from said band.

CHARLES N. METCALF.

CERTIFICATE OF CORRECTION.

Patent No. 2,229,758.

January 28, 1941.

CHARLES N. METCALF.

It is hereby certified that error appears in the printed specification of the above numbered patent requiring correction as follows: Page 3, first column, line 65, claim 2, for the word "outer" read --other--; and that the said Letters Patent should be read with this correction therein that the same may conform to the record of the case in the Patent Office.

Signed and sealed this 4th day of March, A. D. 1941.

(Seal)

Henry Van Arsdale,
Acting Commissioner of Patents.
